UNITED STATES PATENT OFFICE.

CHARLES C. MCCOLLY, DECEASED, LATE OF WAYNE, COLORADO, BY JOSIAH MCCOLLY,
ADMINISTRATOR, OF WAYNE, COLORADO, ASSIGNOR OF ONE-HALF TO CARMAN E.
LOOKINGBILL, OF MAXWELL, IOWA.

BOLTING MECHANISM.

1,104,434.

Specification of Letters Patent.

Patented July 21, 1914.

Application filed June 28, 1912. Serial No. 706,540.

To all whom it may concern:

Be it known that I, JOSIAH MCCOLLY, a citizen of the United States, residing at Wayne, in the county of El Paso and State of Colorado, am administrator of the estate of CHARLES C. MCCOLLY, deceased, late of Wayne, in the county of El Paso and State of Colorado, who in his lifetime invented a new and useful Bolting Mechanism, of which the following is a specification.

One object of the present invention is to provide novel means for locking the doors of a combined end gate and shoveling board.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings, Figure 1 shows the invention in elevation; Fig. 2 is a longitudinal section; Fig. 3 is a transverse section; Fig. 4 is an elevation showing the locking bolts in unlocked position; Fig. 5 is a detail enlarged from Fig. 1; and Fig. 6 is a detail perspective of the lower striking plate and adjacent mechanism.

In the drawings there is shown a supporting structure comprising a top plate 1 and spaced side bars 2. Angle members 3 are provided, certain flanges 4 of which overlap the forward faces of the top plate 1 and of the side bars 2, the angle members 3 constituting means for holding the top plate and the side bars together. The other flanges 5 of the angle members 3 project forwardly and constitute the side walls of the combined end gate and shoveling board. The drawings show angular hinge members 6, the members 6 being secured to the flanges 4 and 5 of the angle members 3, the hinge members 6 serving as reinforcing elements for the flanges 5 which constitute the side walls of the shoveling board. The hinge members 6 are knuckled as indicated at 7 upon other hinge members 8 and 9, the hinge members 8 and 9 being connected with doors 10. One flange 12 of an angle member is secured to the lower edge of the top plate 1, the other flange 11 thereof constituting

an abutment for the doors 10 when the same are in closed position. The flange 12 of the angle member is equipped with a forwardly projecting striking plate 14. One flange 15 of another angle member is secured to the lower ends of the side bars 2, the other flange 16 of the angle member constituting an abutment for the lower ends of the doors 10. The flange 15 is provided with an outstanding striking plate 17 projecting through communicating notches 18 in the lower portions of the meeting edges of the doors 10. At this point it may be noted that the flange 15 constitutes a closure for the notches 18. If desired, the doors 10 may be peripherally bound as indicated at 19.

The inner ends of the hinge members 8 terminate in guides 20. These guides 20 overlap the inner ends of the hinge members 9 and, in combination with the locking mechanism hereinafter described, constitute means for holding the doors in closed position. Mounted to slide in the guides 20 of the hinge members 8 are locking bolts denoted by the numerals 21 and 22. The upper locking bolt 21 is adapted to engage with the striking plate 14 and the lower locking bolt 22 is adapted to engage with the striking plate 17. Secured to one of the doors 10 adjacent the free edge thereof is a wear plate 23 to which a reversely curved lever 24 is united intermediate its ends, by a primary pivot element 25. By means of secondary pivot elements 26, the adjacent ends of the locking bolts 21 and 22 are pivotally connected with the lever 24 upon opposite sides of the pivotal connection 25 upon which the lever 24 swings. The adjacent ends of the locking bolts 21 and 22 are curved in opposite directions to define concaved seats 27 in the inner edges of the locking bolts. Adjacent its ends, the lever 24 is equipped with projections in the form of bosses or studs 28.

Referring particularly to the locking mechanism, it will be understood, noting particularly Fig. 5, that the lever 24 may be swung upon its pivotal mounting 25 so as to advance the locking bolts 22 and 21 in opposite directions, so that the locking bolt 22 will engage with the striking plate 17, the locking bolt 21 engaging with the striking plate 14. When the parts are thus posi-

tioned, the bosses 28 will engage in the concaved seats 27 of the locking bolts, the bosses 28 engaging with the locking bolts upon opposite sides of a line, parallel to the locking bolts, and passing through the pivotal mounting 25 of the lever 24. The construction, therefore is such that when the parts are positioned as shown in Fig. 5, the locking bolts 21 and 22 cannot become disengaged with their respective striking plates, saving by manual manipulation of the lever 24. The locking bolts 21 and 22 are thus held positively in engagement with the respective striking plates and no matter how strong a thrust is applied to the locking bolts, in a direction parallel to the long dimension of the lever, the locking bolts cannot thereby become disengaged from the striking plates. It will be understood readily, that the locking bolts 21 and 22 may be disengaged respectively, from the striking plates 14 and 17, by swinging the lever 24 into the position shown in Fig. 4. It is to be observed that the adjacent ends of the locking bolts 21 and 22 are curved in opposite directions, and that the lever 24 is reversely curved. Owing to this construction, it will be exceedingly difficult to move the locking bolts 21 and 22 to unlocked positions, accidentally, as, for instance, by means of a force applied to one locking bolt at the point indicated by the arrow A in Fig. 1.

Having thus described the invention, what is claimed is:—

1. In a device of the class described, a pair of keepers; oppositely extended locking bolts slideable in the keepers and having rigid inner ends provided with concavities in their opposite edges; a lever; a primary pivot element engaging the intermediate portion of the lever; secondary pivot elements connecting the rigid ends of the bolts with the lever upon opposite sides of the primary

45 pivot element and upon opposite sides of a line parallel to the bolts and passing through the primary pivot element; and studs upon the lever adjacent its ends and independent of the secondary pivot elements, the studs being engaged in the concavities of the rigid ends of the bolts upon opposite sides of said line when the bolts are moved to locked 50 positions, the studs constituting means whereby the lever may be swung.

2. In a device of the class described, a pair of keepers; oppositely extended locking 55 bolts slideable in the keepers and having rigid inner ends; a lever; a primary pivot element supporting the lever; secondary pivot elements uniting the rigid ends of the bolts and the lever upon opposite sides of the primary 60 pivot element; and a stud upon one end of the lever and independent of the secondary pivot element, the stud engaging the rigid end of one bolt to one side of a line parallel to the bolts and passing through the primary 65 pivot element when the bolts are advanced into locked positions.

3. In a device of the class described, a keeper; a locking bolt slideable in the keeper and having a concavity in one edge; a lever; 70 a fulcrum for the lever; a projection on the lever, engaged in the concavity of the locking bolt; and a pivot element connecting the locking bolt with the lever, intermediate the projection and the fulcrum of the lever. 75

In testimony that I claim, as administrator of the estate of CHARLES C. McCOLLY (deceased), the foregoing as my own, I have hereto affixed my signature in the presence of two witnesses.

JOSIAH McCOLLY,
Administrator of the estate of Charles C.
McColly, deceased.
